UNITED STATES PATENT OFFICE

JOSEPH A. WHITE, OF MELROSE PARK, PENNSYLVANIA, ASSIGNOR TO THE MOORE & WHITE COMPANY, OF PHILADELPHIA, PENNSYLVANIA, A CORPORATION OF PENNSYLVANIA

ROTARY SCREEN

Application filed October 31, 1930. Serial No. 492,592.

My invention relates to certain improvements in rotary screens for paper stock.

One object of my invention is to so design the mechanism that the paper stock will pass through the rotary screen from the inside to the outside, and the action of the diaphragms, which are located on the outside of the cylinder, will be to force the water from screened stock back through the screens into the unscreened stock, thus making the screening process more efficient.

A further object of the invention is to make a clean pulp and to prevent strain on the diaphragms.

15 The invention also relates to the mechanism for operating the diaphragms.

In the accompanying drawings:—

Fig. 1 is a longitudinal sectional view of my improved rotary screen;

20 Fig. 2 is an end view;

Fig. 3 is a transverse sectional view on the line 3—3, Fig. 1;

Fig. 4 is a plan view;

25 Fig. 5 is a detached view of the rocker bar; and

Fig. 6 is a detached view of one of the bumpers.

Referring to the drawings: 1—1 are the 30 end frames of the machine. Extending from one end of the frame to the other is a semi-circular vat 2, in the present instance, made up of three longitudinal plates flanged at each edge as shown in Fig. 3, but the vats can be constructed in any manner desired without departing from the essential features of the 35 invention.

Mounted in bearings 3—3 in the frames 1 are the trunnions 4 of the rotary screen cylinder 5. This screen has open heads 6 and a series of longitudinal ribs 7, and between these ribs are the screen plates 8, through which the stock passes from the interior of the screen to the vat. Each head 6 consists of a hub 9, connected to a ring 10 by spokes 11, so that the liquid can freely flow through these heads.

50 Tailings feeding plates 12 project into the screen from two of the ribs in the present instance, and these plates are beveled from the inlet end of the machine towards the tail-

ings outlet. The plates are curved at their outer ends as at 13, to form scoops to more readily carry the tailings. This arrangement causes the tailings to be conducted to the discharge end of the screen, preventing the tailings becoming broken up and difficult to remove.

55 The screen is driven from one end of the machine and on the trunnion 4 at this end of the machine is a gear wheel 14, which meshes with any suitable driving gear. Between the screen and the vat are two sets of curved diaphragms 15. These diaphragms are perforated at intervals as shown. The diaphragms are carried by levers 16, pivotally mounted on longitudinal shafts 17 extending the full length of the machine. These shafts have their bearings in boxes 18 on the end frames 1—1. The inner arm of each lever is curved as shown in Fig. 3, and extends well into the vat. The inner arm 19 of each lever is securely attached to a diaphragm 15. The outer arm 20 of each lever extends on the outside of the vat, as shown clearly in Fig. 3. At one side of the machine is a power shaft 21, mounted in suitable bearings 22, and on this shaft are two eccentrics 23. The strap 24 of each eccentric has an arm 24a, and resting on this arm is a block 25, which extends into a socket 25a in an arm 20 on the side of the machine. The two arms on the side of the machine next to the shaft 21 are spaced apart, and each arm is actuated by an independent eccentric on the shaft, so that as the shaft rotates the arms are reciprocated, and this motion is imparted to the diaphragms 15, causing them to move to and from the perforated periphery of the cylinder 5. In order to impart a like movement to the levers 16 on the opposite side of the machine, the levers on the shaft of the machine are connected to those on the opposite side by a bar 31. Each bar extends into a socket in the two levers, as shown clearly in Fig. 3, so that when the eccentric reciprocates, the opposite lever is reciprocated in the same manner.

60 The two eccentrics on the shaft 21 are set opposite each other, so that when one set of diaphragms is moving towards the cylinder, the other set of diaphragms is mov-

ing away from the cylinder. Connecting the two sets of levers is a rocker 30, adapted to rock on a block 44 carried by a plate 45, adjustably mounted on a beam 46, secured to brackets 47 on the end frames of the machine. Each end of the rocker 30 is notched at 48 and engages the arms 20 of the levers on that side of the machine, so that when motion is imparted to one set of levers, this motion is transmitted to the other set, insuring the positive action of both sets of diaphragms without lost motion. A flexible bumper 49 is located in back of each end of the rocker 30. These bumpers are secured to a plate 50, which plate is attached to the bar 46 in the same manner as the plate 45, the bumpers preventing chattering of the parts. By this construction there is a substantially continuous movement of the stock through the screen.

32 is the inlet to the interior of the screen and 33 is the outlet from the vat. The water is discharged from this outlet 33 over a weir 34, so that the water in the vat will be of a given height. At the opposite end of the machine is a tailings receptacle 35, which receives the tailings from the screen as they are fed from the screen, and on the head at this end of the screen is a bucket 36, which dips into this tailings receptacle 35, removing a certain amount of the tailings and discharging it into a hopper 37, which directs them to a point outside of the machine. While in the drawings I have shown a dipper for picking up the liquid and discharging it into a hopper 37, in some instances this dipper may be dispensed with, without departing from the essential features of the invention.

40 In order to close the space between each end frame and the head of the cylindrical screen below the water line, suitable packing 38 is used. At one end of the vat is an opening closed by a cap 39, and in order to drain the bottom of the vat without removing the cap, a discharge valve 40 is located at the lowest point of the vat. 41 is a draining valve for the outlet 33, and 42 is a drainage valve for the tailings receptacle. In some instances, in order to clean the screens thoroughly, a jet pipe 43 is located at either side of the cylinder above its center of rotation, according to the direction of rotation of this screen, and water jets from the pipe play upon the screens of the cylinder and dislodge any material carried by the screens.

45 The stock is fed into one end of the cylinder and is screened outwardly through the screen plates to the vat. The tailings either settle or float and pass through the screen cylinder and out the opposite end of the said cylinder into the tailings receptacle, and they are removed from this receptacle by the bucket 36. The diaphragms being located in the vat outside the cylinder and in the screen stock, they

are free from tailings, etc. The films of fibre which naturally form against the inner surfaces of the screen plates, make a perfect filtering mat for catching the fine tailings, and this film being constantly discharged at one end of the cylinder, positively removes the fine dirt that would otherwise go through the screen. The fibres, separate from the dirt, return with water back to the cylinder. The action of the diaphragms outside the cylinder forces the water from screened stock back through the plates into the unscreened stock, thus making the screening process much more efficient. The screening action due to the movement of the diaphragms is caused by suction instead of by pressure, as in the case of screens screening from the outside of the cylinder to the inside thereof. The present construction makes clear pulp and prevents strains on the diaphragm.

I claim:

1. The combination in a rotary screen, of a vat; a cylindrical screen mounted in the vat; diaphragms located between the screen and the inner walls of the vat; means for vibrating said diaphragms; an inlet for the stock, communicating with the interior of the cylindrical screen; a discharge, communicating with the vat, so that as the diaphragms are vibrated the stock will be drawn through the screen into the vat; and a tailings receptacle at the end of the screen opposite to the inlet opening.

2. The combination in a rotary screen, of a vat; a cylindrical screen mounted in the vat; diaphragms located between the screen and the inner walls of the vat; means for vibrating said diaphragms; an inlet for the stock, communicating with the interior of the cylindrical screen; a discharge, communicating with the vat; so that as the diaphragms are vibrated the stock will be drawn through the screen into the vat; a tailings receptacle at the end of the screen opposite to the inlet opening; a bucket carried by the screen and arranged to remove the tailings from the tailings receptacle; and a hopper into which the tailings are discharged from the bucket.

3. The combination in a rotary screen, of two end frames; a semi-cylindrical vat located between the end frames; a cylindrical screen open at each end and partly submerged within the vat; a trunnion at each end of the screen; bearings in which the trunnions are mounted to allow the screen to be rotated; an inlet at one end of the machine communicating with the interior of the rotary screen; an outlet at the same end of the machine communicating with the vat; a tailings receptacle at the opposite end of the machine and communicating with the interior of the screen; means within the screen for directing the tailings to the tailings receptacle; and means for removing the tailings from the tailings receptacle.

4. The combination in a rotary screen, of a frame at each end of the machine; a semi-cylindrical vat mounted between the frames; a rotary screen partly submerged within the vat, said screen being open at each end; an inlet for the stock at one end of the machine communicating with the interior of the screen; a discharge opening for the stock communicating with the vat at the same end of the machine as the inlet opening; a tailings receptacle at the opposite end of the machine and communicating with the interior of the screen; and longitudinal tailings feeding plates projecting from the inner walls of the screen for directing the tailings towards the tailings receptacle. 70

5. The combination in a rotary screen, of a frame at each end of the machine; a semi-cylindrical vat mounted between the frames; a rotary screen partly submerged within the vat, said screen being open at each end; an inlet for the stock at one end of the machine communicating with the interior of the screen; a discharge opening for the stock communicating with the vat at the same end of the machine as the inlet opening; a tailings receptacle at the opposite end of the machine and communicating with the interior of the screen; and longitudinal tailings feeding plates projecting from the inner walls of the screen, said plates being curved at their outer edges to carry the tailings to the tailings receptacle. 85

6. The combination in a rotary screen, of a vat; a rotary screen partly submerged within the vat, said screen being open at each end; an inlet for the stock discharging into the interior of the screen; an outlet communicating with the vat; diaphragms in the vat; means for vibrating the diaphragms towards and from the screen, the parts being so arranged that when the machine is in operation a film of fibre forms against the inner faces of the plates of the screen, making a perfect filter for catching fine tailings; and means for constantly discharging the film at one end of the machine, the film carrying with it the fine dirt that would otherwise pass through the slots of the screen. 90

7. The combination in a rotary screen, of a vat; a cylinder in the vat; means for rotating the cylinder; two sets of diaphragms between the cylinder and the bottom of the vat; a cam for operating each set of diaphragms; a shaft on which the cams are mounted, said cams being raised so that the diaphragms of one set will move towards the cylinder while the other set is moved away from the cylinder; means for connecting the diaphragms on one side of the cylinder with those on the opposite side; and a rocker connecting one set of diaphragms with the other set on the side of the machine opposite the shaft. 105

8. The combination in a rotary screen, of

JOSEPH A. WHITE.
